US00D619462S

(12) **United States Design Patent**
Cummings et al.

(10) **Patent No.:** US D619,462 S
(45) **Date of Patent:** ** Jul. 13, 2010

(54) **LOWER PORTION OF A BOTTLE**

(75) Inventors: **Bruce Cummings**, New York, NY (US);
Simon Dutton, New City, NY (US);
Caroline Fontana, Puteaux (FR); **Isaac Milhem**, Jersey City, NJ (US); **Guilhem Rousselet**, St. Maur (FR); **Nick Verebelyi**, London (GB)

(73) Assignee: **Colgate-Palmolive Company**, New York, NY (US)

(**) Term: **14 Years**

(21) Appl. No.: **29/339,937**

(22) Filed: **Jul. 10, 2009**

(51) LOC (9) Cl. **09-01**

(52) U.S. Cl. **D9/516**

(58) **Field of Classification Search** D9/516,
D9/520, 530, 537, 540, 543, 549, 551, 556,
D9/557, 564, 569, 570, 571, 575; 215/381-385
See application file for complete search history.

(57) **CLAIM**

The ornamental design for a lower portion of a bottle, as shown and described.

DESCRIPTION

FIG. 1 is a front perspective view of a lower portion of a bottle showing our new design;

FIG. 2 is a rear perspective view thereof;

FIG. 3 is a left side view thereof;

FIG. 4 is a right side view thereof;

FIG. 5 is a rear view thereof;

FIG. 6 is a front view thereof;

FIG. 7 is a top view thereof; and,

FIG. 8 is a bottom view thereof.

All broken lines shown in the drawings are for environmental purposes only and form no part of the claimed design.
